UNITED STATES PATENT OFFICE.

JAMES W. CRUIKSHANK, OF PITTSBURGH, PENNSYLVANIA.

APPARATUS FOR DELIVERING ABRASIVE MATERIAL.

1,089,909.

Specification of Letters Patent. Patented Mar. 10, 1914.

Application filed June 4, 1913. Serial No. 771,639.

To all whom it may concern:

Be it known that I, JAMES W. CRUIKSHANK, a citizen of the United States, residing at Pittsburgh, in the county of Allegheny and State of Pennsylvania, have invented certain new and useful Improvements in Apparatus for Delivering Abrasive Material, of which the following is a specification.

10 My invention relates to the art of grinding and polishing plate glass and refers particularly to grading and classifying apparatus for the abrasive, so constructed as to adapt it to the classification as to varying 15 degrees of coarseness, with means for extracting the abrasive material in suspension from the classifying or settling chambers, and supplying it to the grinding table in progressive grades as required in the 20 process.

The apparatus consists generally of a preliminary sump pit or well into which the abrasive and water from the grinding machine flows, a secondary chamber or well 25 into which the contents of the preliminary well are pumped, and wherein the grading and settling operations are performed, with means for lifting the abrasive in suspension from the several compartments within the 30 secondary well, embodying air lift pumps so arranged as to deliver the abrasive as required to the grinding machine where it is utilized, with means for collecting and returning the overflow to the preliminary well.

35 In the drawings, illustrating one preferred installation of the apparatus,—Figure 1 is a general plan view showing the usual plate glass grinding machine and my improved apparatus in connection therewith. 40 Fig. 2 is a vertical cross sectional view indicated by the broken line II. II. of Fig. 1, the grinding machine and its superimposed parts being shown in elevation. Fig. 3 is a vertical sectional view through the preliminary well and settling chambers, at right angles to the construction shown in Fig. 2, and indicated by the section line III. III. of Fig. 1.

45 In the drawings, 2 represents the rotating table of a plate glass grinding and polishing machine of usual construction provided with the usual rotating runners 3, 3.

A centrally arranged distributing trough 4 having pivotally mounted spouts 5, 5, depending below suitable framework, is adapted 50 to receive and distribute the abrasive

material as it is delivered to the central distributing trough, in the same manner as disclosed in patent of Hachmeister, dated June 3, 1913, No. 1,063,434. The table 2 is surrounded by an annular surrounding collecting trough or ditch 6, from which by chute or conduit 7 the surplus abrasive and water pass to a screen 8 interposed between the collecting ditch and the preliminary or sump pit 9. This pit operates to collect all of the surplus material, or any fresh sand or abrasive which may be discharged to it through the screen 8, and is provided with a dividing partition 10 extending part way toward the bottom.

An air lift pump 11, of any suitable construction but preferably of the type illustrated and described in my companion application filed herewith, Serial No. 771,640, is located in the lower portion of the sump pit 9 beyond partition 10, from which an upwardly extending pipe 12 delivers the abrasive into the upper portion of the secondary or grading pit 13. This pit is preferably provided with a vertical partition 14 extending downwardly from the top a portion of the distance toward the bottom, providing for a downward circulation toward the preliminary or initial grading chamber 15 containing the first air lift pump for the coarser abrasive. Beyond partition 14 are similar partitions 15, 16, extended upwardly from the bottom of the main pit, terminating at successively increasing distances therefrom, and preferably above the lower edge of partition 14, thus providing additional supplemental abrasive collecting compartments 13^a, 13^b, similar to the initial abrasive collecting compartment 13^a, and adapted to receive and collect successively finer grades of the abrasive as it is discharged thereto by the upwardly traveling main current. Air lift pumps 17, 18, 19, similar to pump 11, are located in the lower portions of said compartments 13^a, 13^b, 13^c, the upper portion of the main chamber 13 being provided with an overflow pipe 20 of limited cross sectional area passing to the sewer 23, preferably inclined toward any point of discharge. The preliminary or sump pit 9 is also provided at its upper portion with an overflow pipe 22, leading to sewer 23, and also at its upper portion with an overflow pipe 21 leading into the upper portion of the initial chamber 13^a between the main wall and partition 14. Pipe 21

is preferably of more slightly increased cross sectional area than pipe 20.

The several air lift pumps are provided with the downwardly deflected centrally disposed water jet nozzles 24 communicating with water supply pipes 25 having regulating valves 26 connected to the water supply main pipe 27. The pipes 25 are also preferably provided with stop cocks 28, 10 which may be set so as to provide for a constant and predetermined flow of water, irrespective of the opening of valves 26.

Air is supplied to the several air lifts by pipes 32, connected with any suitable source 15 of pressure supply, and having the necessary controlling valves, not shown. The several air lift conduits 17^a, 18^a, 19^a, are connected by a manifold or header 28, from which a common conduit pipe 29 leads 20 downwardly for distribution of the water and abrasive to the middle main trough 4. Upwardly above the connections to manifold 28, and above connection to pipe 12, each of the air lift pipes is provided with 25 supplemental vertical pipes 30, each having at its upper end a regulable outlet valve 31 for escape of air.

The operation is as follows: Pit 9 being filled with water and abrasive material in 30 any suitable manner which settles to the bottom in a layer more or less deep and embedding the air lift pump 11, air and water are supplied to the air lift by operation of the necessary valves, allowing sufficient 35 water to pass downwardly into the tightly compacted abrasive through terminal 24, commingling and mixing the abrasive. The sand and water, together with the water from the pit, due to the lifting action of the 40 air supply and the variation in specific gravity, will then pass upwardly through the conduit pipe 12 and into the upper portion of the main grading tank 13 behind the partition 14. Said partition will cause the 45 mixture to flow downwardly until it reaches the lower end of the partition, when the surplus water carrying in suspension some of the lighter abrasive, will pass upwardly through the main well 13 toward outlet 20 50 across the upper portion of partitions 15 and 16. The coarser abrasive will settle into the bottom of compartment 13^a, the next finer grades of material being collected in the succeeding compartments 13^b, 13^c. 55 The first air lift pump 17 is then put into operation with a suitable supply of air and water so that the mixture of sand and water passing to the grinding machine through the pipe 17^a, header 28 and pipe 29 to the grinding 60 machine will be of the proper consistency for the first stage of the grinding operations. The sand and water passes off from the periphery of the grinding table 2 into the surrounding ditch 6 and thence back 65 wardly through screen 8 to the sump pit 9,

where it collects for removal to the settling compartment 13, as above described. During the operation of the pump 17, the surplus water delivered by pipe 12 passes upwardly through chamber 13, carrying with it the finer grades of sand, as stated, the material deposited in each successive chamber being progressively finer, due to the decrease of force of the upward current of water, on account of the progressively increasing area of the main chamber. Surplus water, practically free from abrasive, will thus pass off through the outlet pipe 20 to the sewer, carrying with it any light, useless waste material. Outlet pipe 20 is preferably of a fixed cross sectional area so as to allow for only a certain amount of water to pass upwardly and out through it, the excess of water passing back into the sump pit 9 by means of the overflow pipe 21, or 70 if preferred, to the sewer or other suitable discharge. The overflow pipe 21, as shown, is so located and arranged as to provide an outlet from the chamber 13 at a level just slightly above the sewer outlet 20, so that 75 when the inner end of pipe 20 is submerged, the surplus water will pass out through pipe 21 back to sump pit 9. It will thus be seen that the area of the pipe 20 regulates the maximum upward current of water 80 through the chamber 13, and no coarse grains of sand can be carried up and deposited in the fine sand chambers 13^b, 13^c, but will be collected in the first chamber 13^a. After the operation of applying the coarse sand by means of the first air lift pump 17, I then utilize the fine sand that has been deposited in the chamber 13^b, by means of pump 18. In order to prevent a change of 85 condition and a disturbance of the equilibrium of the upward flow, the pump 11 in sump pit 9 is shut down, so that the delivery of sand and water is stopped from the conduit pipe 12, and the sand carried back by the water from the grinding machine is delivered through screen 8 and will accumulate in the pit 9, during the operation of the other pumps; surplus water passing off from sump pit 9 by overflow conduit 22 to sewer 23. It will also be obvious that if pump 18 90 were put into operation before the flow of water was cut off from the supply pipe 12, that there would be a tendency to draw coarse sand over the partition 15 into division 13^b, but on account of all of the water 95 for this part of the operation being supplied through the nozzle 24 of the pump, there can be no upward flow of water from the bottom of division 13^b, derived from division 13^a over partition 15, and consequently no tendency to carry any coarse material over division 15 into the 13^b, which otherwise would be the case due to a void created by the action of the second pump 18. After the termination of the operation 100

of pump 17, pump 18 is then put into use by turning on the air and water supplied by the controlling valves, the water supply being regulated by the stop cock 26^a set for a predetermined supply, so that the graded sand in pit 13^b will be mixed with water in the proper proportion to obtain the consistency required for this part of the operation, the abrasive being furnished to the table by pipe 18^a and the manifold connection to supply pipe 29, as described. After terminating the use of pump 18, the same operation is repeated for supplying sand from the chamber 13^c, the necessary quantity of water and air supply being regulated to suit the conditions, the quality of the sand, etc.

In the operation of each of the several pumps, the surplus air passing up with the water rises through extension pipe 30 and passes off through valve 31, set to allow a predetermined quantity of air to pass and escape, thus preventing any violent pulsation at the delivery end of pipe 29, enough pressure however being retained to assist in forcing the mixture of sand and water down the pipe 29 toward the grinding machine.

It will be understood that the abrasive is supplied at times in a consistency so thick and dense as to require a slight force of air pressure to prevent the pipe from becoming choked. Heretofore, in other apparatus for the same general purpose, utilizing collecting hoppers or cones, the coarse sand hopper was apt to become filled up and to overflow into the receptacles intended for the finer grades of sand. One of the objects of my invention is to provide an apparatus which will give not only practically constant supply, but constant grades of grinding sand, while any over supply is rendered impossible, the flow being so regulated to a maximum amount, avoiding any surplus supply of coarse or other abrasive. Even though any one or all of the several collecting receptacles may become filled up with their respective grades, no bad results will follow, and any unused surplus matter will fall back into the first or coarse sand pit.

A further important advantage is in the facility with which the sand can be supplied to the grinding machine with a varying quantity of water to suit that part of the process where a certain grade of sand is being applied. At times it is necessary to supply the sand with an extremely diminished quantity of water, and while this has been found impractical with other apparatus, owing to the difficulty in carrying the sand with the small quantity of water, I assist the operation by means of the accompanying air current supply.

The advantages of the invention will be readily appreciated by all those familiar with

this class of apparatus. It is comparatively simple, direct, economical, and not liable to breakage or derangement, while being capable of a very accurate adjustment and control. It will be understood that the number of the several compartments, the pumps and their connections, and the design, proportions, or other details of the invention may be changed or modified by the builder or skilled mechanic, but that all such changes are to be considered as within the scope of the following claims.

What I claim is:

1. Apparatus for delivering abrasive material consisting of a preliminary collecting tank, a separate classifying tank, means for removing abrasive and water from the preliminary tank to the classifying tank, and means for removing abrasive and water from the classifying tank and supplying it to a utilizing apparatus.

2. Apparatus for delivering abrasive material consisting of a preliminary collecting tank, a separate classifying tank, means for removing abrasive and water from the lower portion of the preliminary tank to the upper portion of the classifying tank, and means for removing abrasive and water from the classifying tank and supplying it to a utilizing apparatus.

3. Apparatus for delivering abrasive material consisting of a preliminary collecting tank, a separate classifying tank having a series of partitions providing settling compartments of varying heights communicating above the partitions, means for removing abrasive and water from the lower portion of the preliminary tank to the upper portion of the classifying tank, and means for removing abrasive and water from each settling compartment and supplying it to a utilizing apparatus.

4. In apparatus for collecting and delivering abrasive material, the combination of a preliminary collecting tank, a classifying tank having settling compartments and an overflow conduit, means for removing abrasive and water from the preliminary tank to the classifying tank, and a series of air lift pumps for removing the abrasive and water from the settling compartments.

5. In apparatus for collecting and delivering abrasive material, the combination of a preliminary collecting tank, a classifying tank having settling compartments and an overflow conduit, a return overflow conduit connecting the upper portion of the classifying tank with the collecting tank, means for removing abrasive and water from the preliminary tank to the classifying tank, and a series of air lift pumps for removing the abrasive and water from the settling compartments.

6. In apparatus for collecting and delivering abrasive material, the combination

- of a preliminary collecting tank provided with a downwardly extending partition at its upper portion, a supply conduit opening to the upper part of the tank at one side 5 of said partition, an overflow conduit leading from the tank at the other side of said partition, settling and classifying tank, means for removing abrasive and water from the collecting tank to the classifying 10 tank, and an overflow conduit leading from the upper portion of the settling tank to the collecting tank.
7. In apparatus for collecting and delivering abrasive material, the combination 15 with a settling and classifying chamber, of a pump located in the lower portion of said chamber having a conduit provided with a delivery pipe and a pipe extension above the connection therewith having an 20 air escape controlling valve, substantially as set forth.
8. Apparatus for classifying and segregating abrasive material consisting of a tank having a downwardly extending partition at one end, a plurality of collecting and settling compartments divided by partitions of varying height, means for supplying abrasive and water between the downwardly extending partition and the end of 25 the tank to the first of said compartments, an overflow conduit at the other end of the tank, and a series of pumps located in the lower portions of the collecting and settling compartments and adapted to deliver material to utilizing mechanism.
9. Apparatus for classifying and segregating abrasive material consisting of a tank having a downwardly extending partition at one end, a plurality of collecting and settling compartments divided by partitions of varying height, means for supplying abrasive and water between the downwardly extending partition and the end of 30 the tank to the first of said compartments, an overflow conduit at the other end of the tank, a series of pumps located in the lower portions of the collecting and settling compartments, conduits therefrom provided at their upper ends with air escape controlling 35 valves, and a common delivery pipe connected with said conduits below said valves and adapted to deliver material to utilizing mechanism.
10. Apparatus for classifying abrasive material comprising a tank having a series of vertical partitions extending upwardly from its bottom forming settling compartments, a partition extending downwardly to the upper portion of the first settling 40 compartment, a collecting tank, means for supplying water and abrasive therefrom to one side of the downwardly extending partition
- and for taking off the overflow at the other side thereof, means for returning excess overflow from the settling tank to the collecting tank, and a fixedly located pump for each of said settling compartments adapted to remove the abrasive from any particular compartment to a utilizing mechanism.
11. In combination, a settling tank having a series of upwardly extending partitions of increasing height providing individual compartments, a collecting tank, a pump therein connected with and adapted to deliver into the upper portion of the settling tank, a sewer, an overflow conduit from the settling tank to the sewer, an overflow from the settling tank back to the collecting tank, a glass grinding machine having a conduit leading to the collecting tank, and a pump in each settling tank having a delivery pipe leading to the grinding machine.
12. Apparatus for classifying abrasive material comprising a tank having a series of graduated partitions extending upwardly from its bottom forming settling compartments, means for effecting flow of water and abrasive into the first compartment and thence upwardly through the increasing cross area of the tank and across the partitions, and an overflow conduit of predetermined area leading from the upper portion of the tank.
13. Apparatus for classifying abrasive material comprising a tank having a series of graduated partitions extending upwardly from its bottom forming settling compartments, means for effecting flow of water and abrasive into the first compartment and thence upwardly through the increasing cross area of the tank and across the partitions, an overflow conduit of predetermined area leading from the upper portion of the tank, and an additional overflow conduit for surplus water at a higher level than said overflow conduit.
14. The combination with a tank containing abrasive and water, of a pump having a bodily incorporated downwardly directed agitating water supply and controlling means therefor, substantially as set forth.
15. The combination with a tank containing abrasive and water, of a pump having a bodily incorporated downwardly directed agitating water supply and controlling means therefor, and a regulable actuating air supply, substantially as set forth.
- In testimony whereof I hereunto affix my signature in the presence of two witnesses.
